UNITED STATES PATENT OFFICE.

BRADFORD BORDEN, OF WARREN, OHIO, ASSIGNOR TO THE BORDEN COMPANY, OF WARREN, OHIO, A CORPORATION OF OHIO.

PIPE-THREADING TOOL.

1,056,085.

Specification of Letters Patent.

Patented Mar. 18, 1913.

Application filed September 23, 1908. Serial No. 454,333.

To all whom it may concern:

Be it known that I, BRADFORD BORDEN, of Warren, in the county of Trumbull and State of Ohio, have invented certain new and useful Improvements in Pipe-Threading Tools; and I do hereby declare the following to be a full, clear, and exact description of the invention, such as will enable others skilled in the art to which it appertains to make and use the same.

Heretofore adjustable die stocks or pipe threading tools, of the kind used by plumbers and gas and steam fitters for cutting tapered threads on pipes, have commonly comprised a rotatable and longitudinally-movable housing or chaser-carrier; an adjuster, in the form of a single element common to all of the chasers; a post or wedge rotatable with the housing, but not partaking of the longitudinal travel thereof, for automatically controlling the movement of the adjuster during the cutting operation; and a work-holder fixedly mounted on the pipe and toward which the chaser carrier travels during the thread cutting operation, the carrier and the work-holder having a threaded engagement, or its equivalent, to draw the former toward the latter.

It is upon this work-holder that the post or wedge has heretofore been mounted in such manner as to rotate with the chaser carrier but not to move longitudinally therewith. During this latter movement the adjuster has a movement imparted thereto independently of its rotation with the housing, and being in engagement with all the chasers, simultaneously controls them so as to secure uniformity in recession. This independent movement of the adjuster may be

at right angles to the axis of the chaser carrier, as shown in Letters Patent No. 834,454, issued to me October 30, 1906, or it may be concentric to the axis of the carrier as shown in Letters Patent No. 1,005,147, issued to W. A. Neracher and myself October 10, 1911. In the latter instance the adjuster or chaser-engaging plate is rotatable with and independently of the chaser-carrier, and it is by reason of this independent rotation, and the coöperation of the post or wedge, that the recession of the chasers is automatically controlled and the cutting of a tapered thread is effected.

The primary object of my present invention is to dispense wholly with the work-

holders heretofore absolutely necessary in all hand operated tools, and thus avoid the care and trouble required in centering such work-holders on the pipes to be threaded. It is well known that unless the work-holder is properly centered the resultant thread will not be in true alinement with the pipe's axis, the presentation of the cutting threads of the chasers to the end of the pipe being controlled not by the chasers themselves, but by the position which the chaser-carrier is caused to assume by the positioning of the work-holder on the pipe. To prevent the work-holders from slipping it has heretofore been necessary to provide special means for firmly impinging the pipe surface, and this has tended to add to the trouble and expense. By my present invention I have produced an adjustable die-stock or pipe threading tool, of the kind adapted for cutting tapered threads, composed of less parts than has heretofore been possible, and hence the tool may be made with less expense, and its use attended with but little difficulty. And a further object of my present invention is to effect the removal of all burs while positioning the tool relatively to the pipe.

The invention will be hereinafter fully set forth and particularly pointed out in the claims.

In the accompanying drawings, Figure 1 is a front end view. Fig. 2 is a side elevation, partly in section, Fig. 3 is a side elevation of a slight modification. Fig. 4 is a similar view of a second modification, of which Fig. 5 is a part. Figs. 6 and 7 are details.

Referring to the drawings, 1 designates a rotatable and longitudinally movable housing or chaser-carrier, provided, as customary, with oppositely arranged sockets to accommodate handles by which the housing may be manually rotated. Within this housing or carrier are radially-arranged chasers 2, which, according to known means, gradually and uniformly recede as the threading operation progresses; and such chasers are capable of being adjusted to pipes of different sizes. The adjuster is substantially the same as that shown in Letters Patent No. 1,005,147, before mentioned, and comprises a chaser-engaging plate 4 which is shown as detachably locked to a second plate 3 by a clamp 5, and as having

eccentric slots or grooves (see dotted lines Fig. 1) for taking in lugs of the chasers. The chaser-engaging plate 4 not only rotates with the chaser-carrier, but has an independent rotary movement relatively thereto. Hence as the tool is revolved the gradual recession of the chasers will be effected resulting in the cutting of a tapered thread. It is known in the art that under certain circumstances the rotation of the chaser-engaging plate may be effected either wholly by the pressure of the pipe acting longitudinally on the chasers; or by the application of turning power to the chaser-engaging plate. In either event it is necessary to control this independent rotation of the chaser-engaging plate, and heretofore the controlling means has been mounted directly on the work-holder, but according to my present invention the controlling means is connected to a stop which is designed to engage the end of the pipe being threaded, thereby preventing the controlling means from partaking of the longitudinal travel of the chaser-carrier. I have shown the stop or pipe-engaging member in the form of a circular body 6 located centrally of the tool and having a shank 7 which fits in a correspondingly formed opening in a cross bar 8 extending at right angles to the axis of the tool. This cross-bar carries two posts 9 which project through openings in the chaser-carrier. These posts, as pointed out in Patent No. 1,005,147, have diagonal guide-ways for taking in the lugs 10 of plate 3 so as to thereby cause or permit rotation of the chaser-engaging plate 4 during the thread cutting operation. The shank 7 and cross bar 8 are preferably locked together by a screw 12, but in some forms the bar may be loose on the shank.

On about the same plane as the inner edges or threads of the chasers, I form on the exterior of the stop or pipe-engaging member a circumferential shoulder 13 for abutting against the end of the pipe. This engagement of the stop with the pipe prevents the post 9, cross bar 8, and the stop itself from partaking of the longitudinal travel of the chaser-carrier, and by reason of the engagement between the posts and the chaser-engaging plate (or the plate carried thereby) the independent rotation of such chaser-engaging plate is automatically controlled, resulting in a gradual and uniform recession of the chasers. Thus the necessity of employing and carefully mounting a work-holder on the exterior of a pipe is obviated.

For the purpose of centering or guiding the tool in the performance of its work, I provide it with a guiding agency. The stop or pipe engaging member is shown in Fig. 2 as having a reduced portion 6^a for extending

65 into the bore of the pipe and thus form a

centering guide which serves to properly direct the chasers onto the pipe without being attached to the latter as is required in the use of work-holders. I have also shown the end of the reduced or centering portion provided with reaming teeth 14 for removing burs as the tool is being moved into position, but these may be omitted if desired. For pipes of different sizes different stop bodies may be used, and hence by loosening retaining screw 12 one stop may be removed and another inserted. But instead of providing different stops one may serve for pipes of various sizes. For instance, the stop may be formed with a series of step-up shoulders to accommodate pipes of different sizes, and in this event the stop will be adjustably connected to the cross bar so that the shoulder corresponding with the pipe to be threaded may be properly positioned relatively to the chasers. This form is shown in Figs. 3 and 4; the stop has a series of reduced portions forming circumferential shoulders 13^a, and the shank 7^a is elongated and formed with openings 15 to accommodate set screw 12^a, which latter is necessary only when the stop is not in close frictional engagement with the pipe.

For the purpose of affording additional guides or bearings for the threading tool, the housing or chaser-carrier may have a tubular extension 16 to accommodate centering bushings of different thicknesses, one bushing being shown at 17, Fig. 3, and as each bushing is held by a screw 18, the substitution of one for another may be easily accomplished. These bushings are designed to fit on the pipes and form guides for centering the tool. If it be desired to employ leader screws in connection with the threading tool, an internally threaded nut 19 may be held within the tubular extension of the housing by screws 20, such nut being engaged by a leader screw 21. A left-hand leader screw 22 is shown in Fig. 5, with a correspondingly threaded nut thereon, which nut may be substituted for a right-hand nut shown in Fig. 4. But leader screws are objectionable, and they are in no sense necessary to the successful employment of a threading tool embodying my present invention.

The advantages of my present invention will be readily appreciated by those skilled in the art. So far as I am aware I am the first to produce an adjustable die stock or portable pipe threading hand tool capable of cutting tapered threads on pipes of different sizes without the use of a frame or work-holder fixedly mounted on the pipe, and also without employing a leader screw, or its mechanical equivalent, connected to or supported by such frame or work-holder. This is a desideratum long sought but never before obtained in this class of hand tools.

Furthermore, by means of my present invention I am enabled to thread with equal facility pipes which are not even on the end, that is, where the end has not been perfectly cut off, the pipe at one side being of somewhat greater length than on the other side. Under such circumstances the longer portion of the pipe will form the seat for the stop, and the latter will not revolve 5 with the tool. Therefore, by removing or loosening the set screw 12 the cross bar may revolve around the reduced end or shank of the stop. But whether the stop revolve or be fixed so that the cross-bar will revolve 10 on the stop, the result is the same, the cross-bar will ride and revolve on the end of the pipe. The tool in being applied to and while working on a pipe is guided to its work by centering means carried by either 15 the stop or the housing, such centering means engaging with but not secured to the pipe.

I claim as my invention:—

1. A hand tool for cutting tapered threads 20 on pipes comprising, in combination, a rotatable and longitudinally movable chaser-carrier, a series of radially-arranged chasers, a chaser-engaging plate rotatable with and movable independently of said chaser- 25 carrier, a post for controlling the independent movement of said plate, said post being rotatable with said chaser-carrier but not partaking of its longitudinal travel, means with which the pipe or article being threaded is designed to engage for acting on said 30 post to prevent it from traveling longitudinally with the chaser-carrier, and means carried by the tool for centering it on the pipe without being secured thereto.

2. A hand tool for cutting tapered threads 35 on pipes comprising, in combination, a rotatable and longitudinally movable chaser-carrier, a series of radially-arranged chasers, a chaser-engaging plate rotatable with 40 and independently of said chaser-carrier, a member for causing or permitting the independent rotation of said plate, said member being rotatable with said chaser-carrier but not partaking of its longitudinal travel, 45 means with which the pipe or article being threaded is designed to engage for preventing said member from traveling longitudinally 50 with the chaser-carrier, and means carried by the tool for centering it on the pipe without being secured thereto.

3. A hand tool for cutting tapered threads 55 on pipes comprising, in combination, a rotatable and longitudinally movable chaser-carrier having a central opening, a series of 60 radially arranged chasers, a chaser-engaging plate rotatable with and independently of said chaser-carrier, a post controlling the independent movement of said plate, said post being rotatable with said chaser-carrier but not partaking of its longitudinal 65

travel, a guiding agency at the rear of the chaser-carrier, and a cross-bar extending transversely of the chaser-carrier at or near the front thereof and to which the post is connected, said cross-bar having a portion 70 with which the pipe is designed to engage for preventing the cross-bar and the post from traveling longitudinally with the chaser-carrier.

4. A hand tool for cutting tapered threads 75 on pipes comprising, in combination, a rotatable and longitudinally movable chaser-carrier, a series of radially-arranged chasers, a single element common to all the chasers to control the uniform recession thereof, a stop designed to engage with the pipe to be threaded, a cross-bar mounted on said stop, said cross bar being revolvable with the chaser-carrier, a member carried by said cross-bar for controlling said single 80 element, and means carried by the tool for centering it on the pipe without being secured thereto.

5. A hand tool for cutting tapered threads 85 on pipes comprising, in combination, a rotatable and longitudinally movable chaser-carrier, a series of radially-arranged chasers, a single element common to all the chasers to control the uniform recession thereof, means for centering the chaser-carrier on the pipe to be threaded without being secured thereto, a stop designed to engage with the end of the pipe to be threaded, and means rotatable with the chaser-carrier and supported by such stop, said means 90 coöperating with said single element as the chaser-carrier travels over the pipe to control said single element.

6. A hand tool for cutting tapered threads 95 on pipes comprising, in combination, a rotatable and longitudinally movable chaser-carrier, a series of radially-arranged chasers, a single element common to all the chasers to control the uniform recession thereof, a stop located axially of the chaser-carrier and designed to project into and engage with the end of the pipe to be threaded, and means rotatable with the chaser-carrier and supported by such stop, said means coöperating 100 with said single element as the chaser-carrier travels over the pipe to control said single element.

7. A hand tool for cutting tapered threads 105 on pipes, comprising, in combination, a rotatable and longitudinally movable chaser-carrier, a series of radially-arranged chasers, a single element common to all the chasers to control the uniform recession thereof, a centrally arranged body designed to be supported by the pipe to be threaded, said 110 body having a stop on its exterior for engaging the end of the pipe, means rotatable with the chaser-carrier coöperating with said single element as the chaser-carrier travels over the pipe to control said single 115 element.

element, and a support for such means extending radially from said body at the front of the chaser-carrier.

8. A hand tool for cutting tapered threads on pipes, comprising, in combination, a rotatable and longitudinally movable chaser-carrier, a series of radially-arranged chasers, a single element common to all the chasers to control the uniform recession thereof, a centrally arranged body designed to project into and be supported by the pipe to be threaded, said body having a stop on its exterior for engaging the end of the pipe, means rotatable with the chaser-carrier co-operating with said single element as the chaser-carrier travels over the pipe to control said single element, and a support for such means extending radially from said body at the front of the chaser-carrier.

9. A hand tool for cutting tapered threads on pipes, comprising, in combination, a rotatable and longitudinally movable chaser-carrier, a series of radially arranged chasers, a single element common to all the chasers to control the uniform recession thereof, a centrally-arranged body designed to project into and be supported by the pipe to be threaded, means rotatable with the chaser-carrier co-operating with said single element as the chaser-carrier travels over the pipe to control said single element, and a support for such means extending radially from said body at the front of the chaser-carrier, said body having in rear of said chaser-carrier teeth for reaming the pipe to be threaded.

10. A hand tool for cutting tapered threads on pipes comprising, in combination, a rotatable and longitudinally movable chaser-carrier, a series of radially-arranged chasers, a single element common to all the chasers to control the uniform recession thereof, a centrally arranged body designed to project into and be supported by the pipe to be threaded, said body having a stop for engaging the end of the pipe and also having, in rear of the chaser-carrier, teeth for reaming such pipe, means rotatable with the chaser-carrier for co-operating with said sin-

gle element as the chaser-carrier travels over the pipe to control said single element, and a support for such means extending radially from said body at the front of the chaser-carrier.

11. A hand tool for cutting tapered threads on pipes comprising, in combination, a rotatable and longitudinally movable chaser-carrier, a series of radially-arranged chasers, a single element common to all the chasers to control the uniform recession thereof, means rotatable with the chaser-carrier for co-operating with said single element as the chaser-carrier travels over the pipe to control said single element, and a cross-bar arranged perpendicularly to the axis of said chaser-carrier and revoluble with the latter and to which said last mentioned means is connected, such cross-bar having means for engaging the pipe to be threaded to prevent such cross-bar from partaking of the longitudinal travel of the chaser-carrier.

12. A hand tool for cutting tapered threads on pipes comprising, in combination, a rotatable and longitudinally movable chaser-carrier, a series of radially-arranged chasers, a single element common to all the chasers to control the uniform recession thereof, means rotatable with the chaser-carrier but not partaking of its longitudinal travel for co-operating with said single element as the chaser-carrier travels over the pipe to control said single element, a cross-bar arranged perpendicularly to the axis and forward of said chaser-carrier and revoluble with the latter and to which said last mentioned means is connected, such cross-bar being designed to revolve concentrically to the axis of the pipe, and a stop arranged centrally of the cross bar and with which the pipe is designed to engage.

In testimony whereof, I have signed this specification in the presence of two subscribing witnesses.

BRADFORD BORDEN.
